UNITED STATES PATENT OFFICE.

ROY ALFRED PLUMB AND CLARENCE R. WEED, OF DETROIT, MICHIGAN, ASSIGNEES TO
TRUSSED CONCRETE STEEL COMPANY, OF DETROIT, MICHIGAN, A CORPORATION OF
MICHIGAN.

COMPOSITION-BOARD-FORMING MACHINE.

1,232,078.

Specification of Letters Patent.

Patented July 3, 1917

Application filed July 19, 1916. Serial No. 110,083.

To all whom it may concern:

Be it known that we, ROY ALFRED PLUMB and CLARENCE R. WEED, both citizens of the United States, and residents of Detroit, in 5 the county of Wayne and State of Michigan, have invented a new and useful Composition-Board-Forming Machine, of which the following is a specification.

The present invention has reference to a 10 machine for and process of forming a refractory composition board (from fibrous, preferably fireproof, and cementitious materials) suitable for use on roofs, sidings and for general protective purposes; it is designed 15 to overcome objections (due chiefly to the stretching of the belt) to which machines of the continuously moving type are subject, and to secure a greater production than has been possible heretofore in machines of the reciprocating press type. To 20 these ends the invention consists in a movable belt that carries the wet mass from which the shingle or other board is to be made, together with a reciprocating press 25 positioned transversely of the belt and so arranged as to apply pressure successively to the sections or longitudinal portions of the loaded belt; also in a press located with 30 reference to the belt in the manner stated above, said press having its lower platen equipped with suction means whereby the 35 excess water is quickly removed from the mass in the press without the formation of laterally extending channels such as might be caused by rapid compression between two 40 platens of the usual construction; also in a second suction means over which the belt passes as it approaches the press whereby, during the time the belt is stationary under 45 the press, the excess water is partly removed from a portion of the wet mass, thus reducing the time necessary for compression in the press and greatly increasing the output; also in means whereby the upper platen is 50 normally held elevated to allow movement of the belt; and in a process of forming boards wherein relatively large substantially equal areas of the board are simultaneously subjected to suction to withdraw moisture, one 55 of the areas being at the same time subjected to pressure throughout. The invention further consists in the details of construction shown, described and claimed.

In the drawings, Figure 1 is a side view, 60 parts being broken away, showing a pre-

ferred embodiment of the invention. Fig. 2 is a diagrammatic continuation of Fig. 1. Fig. 3 is a part elevation, part section through the lower platen of the press. Fig. 4 is a plan view of the face plate of the 60 lower platen.

The frame of the machine comprises uprights 1 and suitable upper and lower longitudinal bars 2 and 3. This frame supports pulleys or rollers 4, 5, 6, 7, 8, 9, 10 and 11 65 (the former being driven from any convenient source of power, for example, through belt 12 and reduction gearing 13) over which a material carrying belt 15 passes in the direction indicated by the arrow. Suitable connecting and disconnecting means (not shown) is of course employed whereby the power may be thrown on or off at will. Adjacent the under side of the returning run of the belt is a flopper or agitator 18 and a perforated water pipe 19 whereby material clinging to the surface of the belt may be rinsed off. The roller 9 is mounted on weighted arms 20 and co-acts with the roller 8 to form a wringer. A thin 70 sheet 21 (Fig. 3) of a wet mass of hydraulic cement and fibrous material (such as asbestos) is delivered to the upper surface of the belt through a chute or box 22 which receives its supply from a suitable source, say the 75 pipe 23 that leads to a mixer, not shown. The box is preferably provided with adjustable gage and smoothing plates 24 and 24' whereby the depth of the material on the belt is accurately determined. 80

At a point forwardly of the chute 22, the belt (which while tight enough to support the wet mass is nevertheless of such nature as to allow excess water to be withdrawn through it by suction, being preferably 85 formed of felt or the like) passes over a suction box 25 which is connected, by means of a pipe 26, to a suitable exhausting device, also not shown. The belt continuing on its course passes over the lower platen 27 of a 90 reciprocating press, the frame 28 of which extends across the belt and supports the ram cylinder 29 in which the piston 30 is reciprocable; and, rigidly secured to and reciprocable with the piston, is the upper 95 platen 31 of the press. Rising from the platen 31 are lift rods 32, the upper ends of which are joined by a cross frame 33 that rests on the upper end of a piston rod 34, the piston of which is received in the rela- 100 105 110

tively small pull-back cylinder 35 which rests upon and is in alinement with the cylinder 29 of the ram. Water under pressure is supplied to the upper end of the cylinder 29 through the pipe 40, valve 41 (having an actuating handle 42) and pipe 43, and is exhausted therefrom through the pipe 40, valve 41 and exhaust pipe 44, the latter of which preferably leads to a suitable storage tank 45 (Fig. 2) from which the water is drawn by a pump 46 and delivered through an accumulator or constant pressure device, which may be in the form of a cylinder 47 having a piston, the rod 47' of which is weighted at 47" to an extension 48 of the pipe 43. The pipe 43-48 is preferably in constant communication, through the pipe 49, with the lower end of the pull-back cylinder 35. Thus it will be seen that the upper platen is normally held elevated by the pressure of the water in the pull-back cylinder; when, however, the handle 42 is manipulated to open the valve 41, water under the same pressure is admitted to the larger ram cylinder 29 and the platen is forced downwardly into pressing relation to the lower platen.

The lower platen 26 (Fig. 2) is hollowed out to form a suction box in communication with the pipe 26, through the medium of a pipe 50 to which air may be admitted by a valve 51, the handle 52 of which may be actuated from a point near the handle 42 of valve 41 by means of a link 53 and lever 54 or in any other desired manner. When the air is admitted through the valve 51, the suction is of course broken in both the platen and the suction box 25—thus the belt may be drawn over the two suction devices without being subjected to the friction which would arise were the vacuum constantly maintained. The lower platen is faced by a plate 55, secured in place by bolts 56 and having a series of small perforations 58; and a similar plate 59 is used in the suction box 25. These plates are of the same size and are preferably spaced apart a distance equal to a multiple of their lengths. The platen and box 25 might be made in one box divided by a central transverse partition.

Operation.—The wet fibrous hydraulic mass being fed from the chute or box 22 to the belt 15 in the sheet or layer 21 of proper thickness is carried forward by the belt (it being remembered that the upper platen is normally held elevated from the belt) until it is located above the suction box 25, whereupon the belt is stopped and suction applied to remove a considerable proportion of the excess water. The suction is then broken and the power thrown onto the belt to draw the latter forward. Each step of advance is substantially equal to the length of the suction box or of the lower platen. As the sheet comes under the press, the belt is

stopped, the suction is applied and the valve 41 is manipulated to admit water to the ram, whereupon the upper platen is lowered. Thus pressure and suction are simultaneously applied to elements of the sheet as they successively come into registration with the press—this manner of withdrawing moisture from an element of the sheet of relatively large area is of much importance since the moisture is not only removed more rapidly than in an ordinary press, but the laterally extending channels that are apt to be formed by the latter (giving rise to lines of easy fracture as well as detracting from the appearance of the board) are avoided. The moisture is withdrawn from the sheet in a direction at substantially right angles to the plane thereof and from substantially each individual portion of the area at the same time, namely while the press is in operation. In the machine shown, it will be noticed that suction is simultaneously applied to two substantially equal areas of the sheet, one of the areas being also subjected to pressure throughout at the same time. This mode of operation results in a large output and a corresponding reduction in cost, as well as a compact substantial product, and may be executed by machines of construction widely different from that shown.

The sheet is finally removed from the machine in short lengths by any suitable means, not shown, and stacked and subjected to a further very heavy pressure for a considerable period.

Obviously, the details of construction may be varied within wide limits. We do not, therefore, wish to be limited except as indicated by the subjoined claims.

We claim:—

1. A machine for forming refractory composition board comprising a movable belt; means for supplying a layer of wet hydraulic cementitious material thereto, a reciprocating press arranged to squeeze the belt with the material thereon while the belt is stationary, said press comprising a platen having suction means whereby moisture is removed from the material as the latter is squeezed in the press.

2. A machine for forming refractory composition board comprising a movable belt, means for supplying a layer of wet hydraulic cementitious material thereto, a reciprocating press arranged to squeeze the belt with the material thereon while the belt is stationary, said press comprising a platen having suction means whereby moisture is removed from the material as the latter is squeezed in the press, and suction means operative on the material while it is on the belt and before it reaches the press whereby excess moisture is removed from the wet layer.

3. A machine for forming refractory com-

- position board comprising a movable belt, means for supplying a layer of wet hydraulic cementitious material thereto, a reciprocating press arranged to squeeze the belt with the material thereon while the belt is stationary, said press comprising a platen having suction means whereby moisture is removed from the material as the latter is squeezed in the press, and a suction box over which the belt with the material thereon passes on the way to the press whereby excess moisture is removed from the wet layer.
4. A machine of the class described comprising a movable belt, means for supplying a layer of wet hydraulic cementitious material thereto, a reciprocating press having its lower platen disposed beneath the belt and its upper platen disposed above the belt whereby the latter with the material thereon may be squeezed while the belt is stationary, the lower platen having suction means whereby moisture is removed from the material as the latter is squeezed in the press.
5. A machine of the class described comprising a movable belt, means for supplying a layer of wet hydraulic cementitious material thereto, a reciprocating press having its lower platen disposed beneath the belt and its upper platen disposed above the belt whereby the latter with the material thereon may be squeezed while the belt is stationary, the lower platen being fixed and having suction means whereby moisture is removed from the material as the latter is squeezed in the press, and means for causing the upper platen to approach the lower platen.
6. A machine for forming refractory composition board comprising a movable belt, means for supplying a layer of wet hydraulic cementitious material thereto, means for moving the belt at intervals, a suction box over which the belt is drawn whereby excess moisture is removed from the material, means for breaking the suction in the box at will to enable the belt to be drawn over the box without excessive friction, and a press arranged to operate upon the belt and material after they have passed the suction box to further remove moisture from the material.
7. A machine for forming refractory composition board comprising a pair of perforated suction intake elements, a belt arranged to pass over said elements, the intake element over which the belt passes last being located in a platen of a reciprocating
- press, means for supplying a layer of wet fibrous plastic material to the belt, a reciprocating platen arranged to coöperate with the platen in which the intake element is located to squeeze the material, means for applying suction to both intake elements, means for breaking the suction to both elements, and means for moving the belt across the suction elements while the suction is broken, whereby friction is avoided.
8. A machine for forming refractory composition board comprising two perforated suction intake elements of substantially the same area and shape, a belt arranged to pass over said elements, the intake element over which the belt passes last being located in a platen of a reciprocating press, means for applying a layer of wet fibrous plastic material to the belt, a platen arranged to coöperate with the platen in which the intake element is located to squeeze the material on the belt, and means for drawing the belt forwardly step-by-step, the arrangement being such that an area of the belt which registers with the first intake element at one step registers at a later step with the other intake element.
9. In combination, a belt, means for supplying a layer of wet plastic material thereto, a reciprocating press including a suction platen across which the belt passes, another platen coöperating therewith, and means for moving the belt, whereby the moisture may be expelled from relatively large transverse elements of the material as they are drawn step by step into registration with the suction platen.
10. A machine for forming refractory composition board comprising a movable belt, means for moving the belt, means for supplying a well-mixed layer of wet fibrous hydraulic cementitious material thereto, a reciprocating press arranged to simultaneously squeeze all portions of a considerable area of material on the belt while the belt is stationary, said press comprising a platen having suction means whereby moisture is simultaneously removed from the various portions of the area, means tending to constantly apply suction to the platen, and means for breaking said suction at will, whereby the belt may be moved across the platen without excessive friction.
